(57) CLAIM

The ornamental design for work light, as shown and described.

DESCRIPTION

FIG. 1 is a perspective view of my design;

FIG. 2 is another perspective view thereof;

FIG. 3 is a front view thereof;

FIG. 4 is a left side view thereof, the right side view being a mirror image thereof;

FIG. 5 is a top view thereof; and,

FIG. 6 is a bottom view thereof.

The broken line disclosure represents portions of the work light which form no part of the claimed design.
